UNITED STATES PATENT OFFICE.

JAY A. HEIDBRINK, OF MINNEAPOLIS, MINNESOTA.

ANÆSTHETIZING APPARATUS.

Application filed February 23, 1924. Serial No. 694,485.

My invention relates to anæsthetizing apparatus, and an object in general is to provide an improved apparatus for delivering gases to be used as an anæsthetic. An object in particular is to provide means whereby a plurality of gases such as nitrous oxid and oxygen may be readily delivered from independent sources of supply in such manner that the flow of oxygen for mixing with the nitrous oxid will be automatically controlled by the quantity of nitrous oxid being delivered so that the percentage of oxygen in the mixture will be the same for different adjustments for the nitrous-oxid control. Another object is to provide means in combination with apparatus of this character whereby either nitrous oxid or oxygen alone may be administered when desired.

The full objects and advantages of my invention will appear in connection with the detailed description, and the novel features of my inventive idea will be particularly pointed out in the claims.

In the accompanying drawings which illustrate one form in which my invention may be embodied,—Fig. 1 is a top plan view of the apparatus. Fig. 2 is a view in vertical section on the line 2—2 of Fig. 1. Fig. 3 is a view in vertical section on the line 3—3 of Fig. 1. Fig. 4 is a view in vertical section on the line 4—4 of Fig. 1. Fig. 5 is a view in horizontal section on the line 5—5 of Fig. 2. Fig. 6 is a view in vertical section on the line 6—6 of Fig. 5. Fig. 7 is a view in vertical section on the line 7—7 of Fig. 5.

As shown in the drawings, there is a pair of arms 14 and 16, the outer ends of which are provided with yokes 18 and 20 within which heads of gas containers 22 and 24 are adapted to be secured by set screws 26 and 28. The container 22 is intended for holding oxygen and the container 24 is intended for holding nitrous oxid. The arms 14 and 16 contain longitudinal passageways 30 and 32 as shown in Fig. 2, with which the gas containers are adapted to be placed in communication by means of needle valves 34 and 36 which constitute reducing valves. The arms 14 and 16 extend out from a central member 38 which is provided with a socket 40 for receiving the upper end of a standard 42. Controlling devices designated in general by the numerals 44 and 46 are arranged for cooperation respectively with the passageways 30 and 32, the inner ends

of which communicate with downwardly turned perforations 48 and 50 formed in blocks 52 and 54 rigidly secured in tubular members 56 and 58 forming part of the controlling devices 44 and 46 and constructed integrally with the central member 38. Slidable blocks 60 and 62 are positioned in the tubular members 56 and 58 and the upper ends of these blocks are provided with annular flanges 64 and 66 containing fiber plugs adapted to engage the outlet ends of the perforations 48 and 50. The blocks 60 and 62 are held resiliently upward by springs 68 and 70, and these blocks may be depressed by staplelike members 72 and 74 which extend loosely through openings formed in the fixed blocks 52 and 54 as will be apparent from Figs. 6 and 7. The staple 74 at its upper end is engaged by the lower surface of a diaphragm 76 forming the upper wall of a chamber 78. A coiled spring 80 rests upon the upper surface of the diaphragm 76 and the tension of this spring may be regulated by a screw 82. The chamber 78 is provided with two outlet openings, one of which indicated at 83 and best shown in Fig. 3 is connected by a tube 84 with an inlet port 86 formed in a valve casing 88 attached to the central member 38, as shown in Fig. 4 and containing a mixing chamber 90 having upper and lower walls 92 and 94 which contain openings controlled by a double ended valve 96 having an upwardly extending threaded stem 98 to which is secured a knurled head 100 by which the valve may be turned so as to entirely close either the opening in the wall 92 or the opening in the wall 94. When one of these openings is closed the other one will be uncovered, while by placing the valve in intermediate position both of these openings will be uncovered. The port 86 for admission of nitrous oxid opens into a space above the upper wall 92. The other outlet from the chamber 78 previously referred to and which is indicated at 101 in Fig. 2 is connected by a tube 102 with a chamber 104 in the upper portion of the controlling device 44 for oxygen. The lower wall of the chamber 104 is formed by a diaphragm 106 which constitutes the upper wall of a chamber 108, this latter chamber being provided with a relief valve 110 as shown in Fig. 7. Referring to Figs. 2 and 7, it will be seen that a disk 112 is engaged with the lower surface of the diaphragm 106. The disk 112 is mounted on

2
 one end of a link 114, the other end of which is pivotally attached to a bracket 116. The link 114 engages the free end of a lever 118 whose intermediate portion engages the top 5 of the staple 72. It is obvious that as the pressure of nitrous oxid in the chamber 78 is increased, the sliding block 60 will be depressed to a greater extent, thus allowing more oxygen to flow out of the lower end 10 of the perforation 48 and up through the openings which contain the arms of the staple 72 so that the oxygen is delivered to the chamber 108 which has an outlet port connected by a tube 120 with a space 121 in the 15 casing 88 below the lower wall 94. When the valve 96 is in intermediate position, nitrous oxid will pass into the mixing chamber 90 from above and oxygen will pass into said chamber from below. From the chamber 20 90 the mixed gases pass through an outlet port 122 into a nipple 124 which when the apparatus is used is connected by a suitable tubing with an inhaler, it being understood that the customary rebreathing bag 25 may be attached at any suitable place in this connection. By referring to Fig. 7, it will be seen that the oxygen chamber 108 is connected to a gauge 126 which registers the percentage of oxygen in the mixture when 30 a mixture of oxygen and nitrous oxid is being administered while by reference to Fig. 6 it will be seen that the nitrous oxid chamber 78 is connected to a gauge 128 which registers the number of gallons of nitrous 35 oxid being delivered per minute. A stop arm 130 is secured to the knurled head 100. When this arm engages the left hand side of a finger 132 secured to the valve casing 88, the valve 96 closes the opening through 40 the lower wall 94 and nitrous oxid only is allowed to pass into the chamber 90 for delivery to the inhaler. When the knurled head 100 is turned to bring the stop arm into engagement with the right hand side of the 45 finger 132, the valve 96 closes the opening through the upper wall 92 and oxygen only is allowed to pass into the chamber 90 for delivery to the inhaler. When the stop arm 130 is in intermediate position, the openings 50 through both the upper and lower walls will be uncovered and a mixture of the two gases will be delivered to the inhaler. As previously explained, the controlling device 44 for oxygen is automatically governed by the 55 pressure of the nitrous oxid which is registered on the gauge 128 in number of gallons per minute and the amount of which may be readily varied by means of the screw 82. The percentage of oxygen in the mixture is, 60 therefore, the same for different adjustments of the controlling device for nitrous oxid. It is obvious that as soon as the knurled head 100 is turned toward the right from the position shown in Figs. 1 and 5, a 65 small amount of oxygen will be admitted to

the mixing chamber 90 for mixing with the nitrous oxid and that as the turning movement is continued, the amount of oxygen is gradually increased and the amount of nitrous oxid is gradually decreased, the supply of nitrous oxid being entirely shut off when the arm 130 engages the right hand side of the finger 132. At an intermediate position of the head 100 the valve 96 will be opened equally at top and bottom. If 70 desired, suitable graduations may be placed on the head 100. Proportioning of the gases is controlled with the greatest facility by turning the head 100 in the proper direction. Furthermore, when the patient is being supplied with a mixture of the gases in the desired proportions, it is an easy matter to turn the head 100 to its left hand limit so as to give the patient a few whiffs of pure nitrous oxid to obtain more complete anesthetizing and then turn the head 100 toward the right so as to re-establish administering the mixture in the desired proportion. 85

I claim:

1. An anesthetizing apparatus having a 90 mixing chamber, two independent sources of supply of gases under pressure connected with said mixing chamber, a controlling device in one of said connections, a controlling device in the other of said connections, a diaphragm in said first controlling device constituting one of the walls of a gas chamber which is connected to said mixing chamber, means associated with said diaphragm for varying the supply of gas to said chamber, 95 a diaphragm in said second controlling device constituting a partition between two separated gas chambers, a passageway connecting said first mentioned gas chamber with one of said separated gas chambers, 100 the other of said separated gas chambers being in the connection between its source of supply and the mixing chamber, a valve for controlling the supply of gas to said last mentioned chamber and connections between 105 said second diaphragm and said valve for opening the latter to an extent in proportion to the pressure of gas in the first of said separated chambers. 110

2. An anesthetizing apparatus having a 115 mixing chamber, two independent sources of supply of gases under pressure connected with said mixing chamber, a controlling device in one of said connections, said controlling device having a diaphragm which constitutes one of the walls of a gas chamber which is connected to said mixing chamber and said controlling device having means associated with said diaphragm for varying the supply of gas to said chamber, a controlling device in the other of said connections, said second controlling device having a diaphragm which constitutes a partition 120 between two separated gas chambers, a valve which controls the supply of gas to one of 125 130

said separated chambers and connecting means between said second diaphragm and valve whereby the latter will be opened to an extent in proportion to the pressure of
5 gas in the other of said separated chambers, a passageway connecting said last mentioned separated chamber with the chamber of said first controlling device, said mixing chamber having separate entrance ports for the gases

which pass said controlling devices, and 10 means operable at will to completely close either of said ports and to progressively open either of them as the other one is progressively closed.

In testimony whereof I hereunto affix my 15 signature.

JAY A. HEIDBRINK.
